OVERHEAD OPTICAL HEAD SUPPORT TRACK FOR A PHOTOREPRODUCTION UNIT

Joseph H. Wally, Jr., and Samuel E. Wilson, Shawnee
Mission, Kans., assignors to Western Blue Print Co.,
Kansas City, Mo.

Filed May 28, 1971, Ser. No. 148,279

Term of patent 14 years

Int. Cl. D16—03

U.S. Cl. D61—1 Q

FIG. 1

FIG. 2

FIG. 3

FIG. 4

FIG. 5

FIG. 6

FIG. 7

FIG. 1 is a perspective view of an overhead optical head support track for a photoreproduction unit showing our new design;

FIG. 2 is a far side elevational view thereof;

FIG. 3 is a left end elevational view of FIG. 2;

FIG. 4 is a top plan view of FIG. 2;

FIG. 5 is a sectional elevational view of FIG. 4 as taken from line 5—5;

FIG. 6 is a sectional elevational view of FIG. 4 as taken from line 6—6; and

FIG. 7 is a sectional elevational view of FIG. 4 as taken from line 7—7.

We claim:

The ornamental design for overhead optical head support track for a photoreproduction unit, substantially as shown and described.
